R. GABRIEL

TOOL HANDLE FASTENING DEVICE

Filed July 9, 1924

UNITED STATES PATENT OFFICE.

RAIMUND GABRIEL, OF NEUSTADT, CZECHOSLOVAKIA.

TOOL-HANDLE-FASTENING DEVICE.

Application filed July 9, 1924, Serial No. 725,120, and in Germany July 3, 1923.

This invention relates to a "tool handle fastening device," for instance to a kind of hand rake, and particularly to such one, the main parts of which are produced by stamping or pressing out from metal plates and which form a suitable and easily exchangeable, and, yet, a secure and rigid connection between the handle and the head of the rake.

The two plates "d" are placed against each other with the sockets pointing in opposite direction and then inserted with their narrow ends into a slit *e* of the rake handle "c" and fastened thereto by means of a screw "i" or similar means. The sockets, in this manner, firmly and securely grip the two halves of the end of the handle.

Upon the accompanying drawing one mode of construction of a rake, according to the invention in question, is shown, as follows:—

Fig. 1 is a plan view,

Fig. 2 a side view,

Fig. 3 a front view thereof, the prongs partly broken away,

Fig. 4 a part-view on a reduced scale, that is showing the head of the rake, the two plates placed upon each other and the handle, and

Fig. 5 a perspective view on an enlarged scale with the two flaps stamped out.

The head "a" of the rake and the handle "c" are connected with each other by means of two connecting plates "d" of semicircular shape, produced by stamping out therefrom a socket being in the cross section of a semi-circular shape and riveted at "f," and the two flaps of the lower plate "d" are likewise so bent and also riveted at "f."

In order to increase the strength of the connecting plates they are provided with strengthening ribs "g," formed by pressing.

The head "a" of the rake is also provided with a slit "k," into which the wide and perforated end of the connecting plate "d" is pushed in such a way that the perforations of the connecting plates "d" coincide with the perforations for the prongs "b" in the head.

The rigid connection between the head and the connecting plates is then simply effected by screwing in the prongs "b" or by fastening them in another suitable manner.

I claim:

A tool handle fastening device comprising a handle with a slit in its lower end and a head having also a slit, two connecting plates lying one upon the other and fitted in the slits and each provided with a socket of flaps cut out from the connecting plates and which are bent and riveted for the reception of the two parts of the end of the handle, substantially as described.

In testimony whereof I have signed my name to this specification.

RAIMUND GABRIEL.
